Joseph J. Flashman, 45 Lyndhurst St., Dorchester,
Boston, Mass. 02124

Filed May 11, 1966, Ser. No. 2,261

Term of patent 7 years

(Cl. D80—9)

Fig. 1.

Fig. 2.

FIG. 4.

FIG. 1 is a front view of the bottle display stand showing my new design;

FIG. 2 is a side view looking to the left of FIG. 1;

FIG. 3 is a side view looking to the right of FIG. 1; and

FIG. 4 is a plan view of the display stand.

The dominant features of my design reside in the portions shown in full lines, the broken line showing of the word Kickapoo in FIG. 1 being for purposes of illustration only.

I claim:

The ornamental design for a bottle display stand, as shown and described.
